CARL N. SCHNEIDER, OF BROOKLYN, NEW YORK, ASSIGNOR TO CLARENCE W. BEERS,
OF BROOKLYN, NEW YORK

DESIGN FOR A HAND TOOL FOR CUTTING TUBING

Application filed February 23, 1933. Serial No. 47,303. Term of patent 3½ years.

To all whom it may concern:

Be it known that I, CARL N. SCHNEIDER, a citizen of the United States, and a resident of the borough of Brooklyn, county of Kings, city and State of New York, have invented a new, original, and ornamental Design for a Hand Tool for Cutting Tubing, of which the following is a specification, reference being had to the accompanying drawing, forming a part hereof.

In the drawing,

Figure 1 is a plan view,

Figure 2 is an elevation, and

Figure 3 is an end view of a hand tool for cutting tubing, embodying my new design.

I claim:

The ornamental design for a hand tool for cutting tubing, as shown.

CARL N. SCHNEIDER.
